UNITED STATES PATENT OFFICE.

CLARENCE J. LAWSON, OF PLAINFIELD, NEW JERSEY, ASSIGNOR, BY DIRECT AND MESNE ASSIGNMENTS, TO COLUMBIA MACHINE & STOPPER CORPORATION, A CORPORATION OF NEW YORK.

APPARATUS FOR DELIVERING BOTTLE-CLOSURES.

1,095,407.

Specification of Letters Patent.

Patented May 5, 1914.

Application filed May 6, 1911, Serial No. 625,428. Renewed December 10, 1913. Serial No. 805,857.

To all whom it may concern:

Be it known that I, CLARENCE J. LAWSON, a citizen of the United States, residing at Plainfield, Union county, New Jersey, have invented a new and useful Improvement in Apparatus for Delivering Bottle-Closures, of which the following is a specification.

My invention relates to apparatus for taking bottle closures of the well known 10 crown type from a mass in a hopper and passing them to the sealing heads of a bottle crowning machine in proper position to be applied to the necks of bottles and my 15 objects are the simplification of such mechanisms and the production of a non-clogging device capable, if necessary, of supplying a plurality of chutes.

In the accompanying drawing Figure 1 is a sectional view of my delivering apparatus; Fig. 2 a view of the back of the apparatus showing the mechanism for causing oscillation; Fig. 3 a detail view of the front cover and valve plates with a properly positioned crown between them; Fig. 4 a like 25 view with a wrongly positioned crown between the plates; Fig. 5 a view of the cover plate button; and Fig. 6 a view of a multiple chute outlet.

The entire apparatus is usually located on 30 the highest part of the crowning machine so that the feed will be performed by gravity.

A hopper 1 receives the crowns in an indiscriminate mass and they slide by gravity 35 down the inclined bottom plate 2 toward the front of the hopper.

A grooved valve plate 3 is mounted at the front, or outlet, of the hopper and is provided with a large sectorial opening 4, preferably semi-circular, and extending from the grooved rim to the hub as shown in Fig. 1. This valve plate is secured to a shaft 5 extending through the hopper and is oscillated thereby. A domed cover plate 6 is 40 also secured to the shaft and is spaced from the valve plate so that a crown may lie flat between the outer face of the valve plate and the inner face of the cover plate at the rims. This distance may be varied by adding or removing washers 7 for the purpose 45 of feeding crowns of different depths.

The domed cover plate forms an extension of the hopper so that the mass of crowns will lie on both sides of the valve plate when the

apparatus is in operation. A partial rotation or oscillation of the valve and cover plates is effected by the friction drive 8, 8', on the main shaft 9. The driven member 8' is slidably mounted on the shaft 10 so that the speed, or number of oscillations per minute, can be varied at will. The outer end of the shaft 10 carries a crank disk 11 which is connected to a reciprocating rack 12 by a link 13. This rack 12 engages a pinion on the shaft 5 so that the rotation of the crank disk will cause the shaft 5 to oscillate or partially revolve through about 180 degrees with a backward and forward motion. This oscillation of the valve plate 3 and cover plate 6 causes the mass of crowns in the hopper to be alternately in free communication with the space inside the domed cover plate and then shut off from it according to whether the opening or the solid part of the valve plate is at the bottom of the hopper. As the plates oscillate the crowns in front of the valve plate are tumbled and those feed out between the two plates when in proper position, being replaced by others from the main mass in the hopper when the valve plate is in open position. The tumbling operation is further assisted by the edge of the opening 4 cutting through the mass of crowns in its path during oscillation.

The rim of the valve plate is provided with a lipped groove 15 at the inner periphery of the rim, with a channel 16, deepened as shown in Figs. 3 and 4 and with a squared inner edge 17.

No attempt is made to select the crowns as all on edge in the domed plate will pass into the space between the two plates and no attempt is made to turn over wrongly positioned crowns. If the crowns are properly 95 positioned, that is flange out, they will pass over the lip 15 and into the reservoir space above the guide chute 18 as shown in Fig. 3. If they are wrongly positioned the lower edge of the flange will catch in the groove 15 and the upper edge will strike the squared shoulder 17 so that the crown cannot pass to the chute, as is shown in Fig. 4.

A boss 19 on the cover plate carries a stud 20 having on its inner end, in the space 105 between the rims of the two plates, a round nosed button 21 held in place by a spring 22. This button, in the path of the caps

between the two rims, causes them to oscillate with the plates but if any resistance is encountered the button is retracted and slides over the crowns. These plates are continuously oscillated and misplaced crowns will fall out by gravity when they have been carried above the shaft line and will mingle with the mass in the hopper.

Properly positioned crowns will pass between the plates into the reservoir space 23 above the chutes from which they will fall into the chutes proper. If a plurality of chutes 18, 24, 25 are used the divisions are carried up as shown in Fig. 6 into this reservoir space and in operation the central chute will fill first and then the overflow will be alternately fed into the two outer chutes.

The groove and channel being free from rigid pins and projections permits the crowns to roll freely in the channel and thus reduces the wear and tear on decorated crowns.

The absence of pockets in the valve plate rim lessens the liability of crowns being caught and wedged.

It is obvious that my apparatus will not

operate with a rotary motion for all crowns carried above the shaft line will fall out of the channel in the valve plate.

I claim:—

In a closure feeding device the combination of a hopper, an inclined bottom therein; a valve plate closing the front of the hopper and provided with an opening extending to the rim thereof whereby communication with the mass of crowns in the hopper is alternately opened and closed; a domed cover plate in front of the valve plate and spaced therefrom; an annular groove in the rim of the valve plate facing the cover plate into which closures may pass; a grooved lip on the extreme outer periphery of the rim adapted to intercept wrongly positioned closures and means for imparting an oscillatory motion to the two plates.

In testimony whereof I have hereunto subscribed my name in the presence of two witnesses.

CLARENCE J. LAWSON.
